UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

DOUBLE-DRUM HOIST.

Application filed June 24, 1925. Serial No. 39,167.

To all whom it may concern:

Be it known that I, FRED M. SLATER, a citizen of the United States, and a resident of Easton, in the county of Northampton 5 and State of Pennsylvania, have invented a certain Double-Drum Hoist, of which the following is a specification accompanied by drawings.

This invention relates to double drum hoists of the type in which one drum or the other is automatically connected to be driven from a reversible motor in accordance with the direction of rotation of the motor.

In a hoist of this type, the drums are provided with drum drivers and a main driver. A main driving head driven in one direction or the other from the motor is provided with automatic clutch mechanism for connecting one drum driver or the other to the 20 main driver. The main driver may be located in different positions relatively to the drums and the clutch mechanism may be between the drums or may be located at one end of the drums and yet cooperate with the drum drivers on opposed portions of the drums.

The objects of the present invention are to enable a rocking pawl or clutch member to be mounted on a main driver located at one 30 end of the drums so that the pawl may rock about an axis transverse to the longitudinal axis of the machine and engage one drum driver or the other. By this construction the drums may be placed close together 35 which in some respects is an advantageous construction and prevents the accumulation of dirt and débris between the drums.

One preferred form of the invention is shown in the accompanying drawings, in 40 which—

Figure 1 is a longitudinal sectional view of a double drum hoist,

Figure 2 is a sectional detail view showing the pawl mechanism in a different position, and

Figure 3 is a detail transverse sectional view partly broken away on the line 3—3 of Figure 1 looking in the direction of the arrows.

Referring to the drawings, any suitable reversible motor, as for instance, an electric motor A may be mounted on the main frame B of the hoist which frame is provided with the standards C having a longitudinal drum shaft D mounted therein. This shaft D

may be either stationary or revolvable as desired, in this instance the shaft being stationary. The drums E and F are rotatably mounted relatively to the shaft D. In this instance the drum E is keyed to the tubular 60 shaft or sleeve G which extends along the drum shaft D and is rotatable thereon and terminates at one end in a drum driver H having the clutch teeth J directed or extending in a radial direction with reference to 65 the drum shaft D or axis of rotation.

The other drum F is rotatably mounted on the tubular shaft or sleeve G and it is to be understood that the sleeve G may, if desired, form an integral part of the drum 70 E, and the drum driver H may be removably secured thereto as by means of a key (not shown). Any suitable construction may be provided whereby the drums may be removed from the drum shaft D and may 75 be separated from each other in dismantling the hoist.

The drum F is provided with the drum driver K in the form of ratchet teeth L extending in a radial direction but facing oppositely to the teeth J. The backs O of each set of teeth are bevelled in order to cooperate with the latch or pawl P carried by the main driver or main driving head Q. 80

This main driver may be in the form of an internal gear R rotatably mounted on the drum shaft D and provided with the pawl carrier S bolted to the internal gear by means of the bolts T and extending into the space between the drum drivers H and 90 K. The pawl P is preferably secured to a pivot pin U as by means of the key or pin V which pivot pin U is pivotally mounted in the pawl carrier S as shown in detail in Figure 3. One end of the pivot pin U is 95 rifled at W and cooperates with a rifle nut X secured in a socket in the arm Y of the forked portion Z of the pawl carrier S by means of the pin α . The opposite end b of the pivot pin U is pivoted in the opposite 100 arm c of said forked portion of the pawl carrier S. The distance between the arms Y and c of the pawl carrier is greater than the length of the pawl P so that as the pawl rocks back and forth between the drum driver J and K the rifled end W of the pivot pin may move longitudinally in the rifled socket X and insure the complete movement of the pawl into engagement with the opposite drum driver. 105

In the operation of the device, the driving motor A may be rotated in one direction or the other as desired to cause one drum or the other to become the haulage drum operatively connected to the motor. The remaining drum is then idle and becomes the tail rope drum as is well understood. If the pawl P is in engagement with drum driver teeth J for one drum when the motor 10 is being rotated in one direction, the reversal of rotation of the drum driver will cause the backs of the teeth J and the action of the rifle bar to rock the pawl on its pivot into engagement with the teeth L of the opposite drum driver and this operation will be automatically carried out in accordance with the reversal of the motor.

I claim:

1. In a hoist, the combination of a main shaft, standards for supporting said main shaft, a pair of drums rotatable about said main shaft, opposed drum drivers at one end of one drum and adapted to rotate through different transverse planes, a main driver at one end of the shaft and connected to be rotated by a reversible source of

power, and a pawl carried by the main driver for connecting one or the other of the drums with the main driver in accordance with the direction of rotation of said main driver. 30

2. In a hoist, the combination of a main shaft, standards for supporting said main shaft, a pair of drums rotatable about said main shaft, a main driver rotatable on one end of the main shaft and connected to be driven by a reversible source of power, opposed drum drivers between the main driver and one of the drums and associated with the drums, said drum drivers being rotatable through different transverse planes, a pawl carrier between the opposed drivers and secured to the main driver, and an oscillatory pawl pivoted to the pawl carrier to cooperate with the drum drivers for connecting one or the other of the drums with the main driver in accordance with the direction of rotation of said main driver. 35 40 45

In testimony whereof I have signed this specification.

FRED M. SLATER.
